(57) **CLAIM**

The ornamental design for a shoe, as shown and described.

DESCRIPTION

FIG. 1 is a front perspective view of a shoe showing my new design;
 FIG. 2 is a side view thereof; and,

FIG. 3 is a rear perspective view thereof.

The oblique shade lines represent a transparent or translucent appearance. The broken lines immediately adjacent to the shaded area define the bounds of the claimed design and form no part thereof. The broken lines depicting the remainder of the shoe form no part of the claimed design.
